Primary Examiner — Michael A Pratt**(57) CLAIM**

The ornamental design for an exhaust pipe set for a minivan, substantially as shown and described.

DESCRIPTION

FIG. 1 is a partial perspective view of the present design showing an exhaust pipe set for a minivan; FIG. 2 is a rear view thereof; FIG. 3 is a side view thereof, the opposite side being a mirror image thereof; FIG. 4 is a top view thereof; FIG. 5 is a partial perspective view of another embodiment of the present design showing an exhaust pipe set for a minivan; FIG. 6 is a rear view thereof; FIG. 7 is a side view thereof, the opposite side being a mirror image thereof and the top view corresponding to FIG. 4; FIG. 8 is a partial perspective view of another embodiment of the present design showing an exhaust pipe set for a minivan; FIG. 9 is a rear view thereof; FIG. 10 is a side view thereof, the opposite side being a mirror image thereof; and, FIG. 11 is a top view thereof.

The bottom view is disclaimed herein. The portions of the design shown in broken/dashed lines are for illustrative purposes only and form no part of the claimed design. The illustrated article is not limited to the scale shown.
